JOHN D. SEABERT, OF DAYTON, OHIO, ASSIGNOR TO GENERAL MOTORS RADIO CORPORATION, OF DAYTON, OHIO, A CORPORATION OF OHIO

LOUD SPEAKER ADAPTED FOR AUTOMOBILE USE

Application filed December 15, 1930. Serial No. 502,453.

This invention relates to acoustical devices such as are adaptable for use with radio receiving instruments.

One of the objects of the invention is to provide a loud speaker, or an acoustical device, that is adapted to be mounted in the roof structure of an automotive vehicle without alteration of said roof structure, and without materially disturbing the continuity of surface of the roof lining or upholstering.

A further object of the instant invention is to provide acoustical devices of the dynamical type that are adaptable for automotive use.

15 A further object of the invention is to provide acoustical devices of the class described having means for baffling or damping the sound vibrations through an effective increase in air path, whereby undesirable reverberations may be eliminated.

Further objects and advantages of the present invention will be apparent from the following description, reference being had to the accompanying drawings wherein a 25 preferred embodiment of one form of the present invention is clearly shown.

In the drawings:

Fig. 1 represents a front view of an acoustic device, part of which is broken away to 30 show the device in section, substantially on the line and in the direction of the arrows 1—1 of Fig. 2.

Fig. 2 is a sectional view, taken on the line and in the direction of the arrows 2—2 of 35 Fig. 1.

Referring to the drawings, and particularly to Fig. 2, a main supporting disc or back plate 20 has attached thereto a cup-shaped field housing 22, by a central pole piece 24 and a reenforcing plate 26. A reduced portion 30 of the central pole piece or core 24 projects through apertures of the base 28 of the field housing 22, the supporting plate 20 and the reenforcing plate 26 and is there riveted or peened over as illustrated, thus securing these four members in position. This structure is adapted to increase the permeability of the base 28 of the field housing 22, though it could be accomplished in any other 45 suitable and well known manner. An annu-

lar pole piece 32, attached to the field housing 22 in any suitable manner, carries a reenforcing ring 34, concentrating the flux density across the air gap 33, between it and the pole piece 24.

55 A field coil 36, having two terminals 38 and 40, connected either to a source of direct current or to a source of rectified current, in order to excite the magnetic field, is disposed within the cup 22 and about the center pole piece 24. Interposed between the field coil 36 and the annular pole piece 32 there is a spacer 42 of any soft packing material that prevents axial movement of the field coil 36, along the core 24.

60 A reentrant diaphragm 44, that includes a pair of frusto conical surfaces 43 and 45, is firmly secured to a hinge or portion 46 constituting a cloth or other flexible ring. This may be accomplished by means of glue or any 65 other suitable binding material applied to their overlapping edges as at 48. The cloth ring 46 is clamped at its outer periphery between two rings 50 and 52, of U-shaped or any other form which guarantees rigidity or 70 great firmness. Screws 54, will accomplish this end, and are threaded into one end of a post 56, the other end of which is riveted or otherwise secured to the supporting disc or 75 plate 20 as at 57. At the center of the diaphragm 44, a cylindrical support 58 is attached, upon which is wound a speech coil 60 having appropriate leads 59 and 61.

80 In order to properly center the cylindrical support 58 with respect to the pole piece 24 and the air gap 33, a spider 64 is cemented or otherwise attached to the diaphragm 44 as at 63, and thence fastened to a reduced portion 65 of the pole piece 24 by a screw 66. The spider 64 being very flexible allows axial 85 movement of the cylindrical support and the speech coil, but at the same time prevents any radial movement thereof.

85 A metal supporting ring 68, located between the posts 56 and supported by the U-shaped ring 52, aids to support a sound absorbing ring member 70. The ring 70 is of suitable pressed fibrous material as excelsior, felt or the like which is located within and 90 substantially fills the space between the posts 100

56 and the cup 22. The ring member 70 prevents free flow of air from one side of the diaphragm 44 to the other side, but guarantees sufficient leakage therethrough to compensate for the differences in the air pressure before and behind the vibrating diaphragm 44 at any instant. This ring member 70 acts also like a baffle which increases in effect at least the path of the air from the inside of the diaphragm to the outside, and thereby improves the acoustic properties of the reproducer. The restricted passages through the porous material of the ring member 70 tend to reduce or dampen out undesired reverberations, prominent in a shallow type reproducer as illustrated. However, the porous baffle is equally applicable to the conventional form of speaker, in whatever instance its use is deemed necessary or advisable.

20 A cover-plate or grille 72 of suitable or desired shape, is provided with several sound openings 74, to allow sufficient air to flow through, and is supported by the studs 76, riveted or otherwise secured at 78 to the supporting plate 20, screws 80 threaded into the said studs securing the grille in place.

25 The unit thus constructed is adapted to be mounted upon the roof structure of an automotive vehicle without alteration of either the unit or the roof structure. This is accomplished by means of screws 82 driven through the back plate 20 of the unit into the bow or batton 83 of the top structure, thus disposing the back plate 20 with its dished portion supporting the motor within the space between two adjacent bows 83, substantially as illustrated in Fig. 2. The unit may be attached to the top before the grille 72 is attached, or the grille may be provided with apertures 84 opposite the screws 82 through which access may be had by a suitable tool for driving the screws 82.

30 The roof structure has been shown only in fragmentary section, but it is readily seen that the fabric 85 of the top upholstery, or the lining as it is known, readily gives between the bows 83 so as to allow disposition of the unit therein. That is to say, in mounting the unit on the top the bows 83 are located and thence the unit is pressed up against them so as to allow driving of the screws 82, which positioning of the unit will stretch the fabric 85 sufficiently to allow the unit to be mounted as stated. After the unit is thus mounted the leads 38, 40, 59 and 61 are appropriately connected with the instrument and electrical sources with which they are designed for operation, and the installation is then complete. This mounting of the speaker unit offers little or no obstruction to the inner contour of the structure, and is not conspicuous in its appearance since the face plate 72 lies close against the inner surface of the top 35 and it may be finished in tone or color to

match with the interior finishing of the vehicle.

While the form of embodiment of the present invention as herein disclosed, constitutes a preferred form, it is to be understood that other forms might be adopted, all coming within the scope of the claims which follow.

What is claimed is as follows:

1. An acoustical device of the class described, comprising in combination, a back plate supporting a motor at its center; a foraminous face plate secured at its periphery to the back plate; supporting studs for the face plate and spacing it from said back plate so as to substantially enclose the acoustical device, a reentrant diaphragm supported on the back member and being disposed concentric with said motor, and a pad of sound absorbing material secured against said back member and disposed about said motor. 85

2. An acoustical device comprising in combination a supporting plate having a driving motor centrally secured thereof; a diaphragm secured at its periphery to the back plate; and means spacing the diaphragm therefrom to provide air passage from one side of the diaphragm to the other; a pad of sound dampening material disposed in the space between the diaphragm and back plate to prevent free air flow from behind the diaphragm; and a face plate secured to the back member enclosing the diaphragm and motor. 90

3. An acoustical device comprising in combination a driving motor, and means supporting the same comprising a back plate; a diaphragm secured in spaced relation to the back plate, so as to provide air flow over the edge of said diaphragm; sound absorbing material substantially filling the space between the diaphragm and back member, but being wholly free of engagement with said diaphragm; said absorbing material being of a fibrous nature to prevent free air flow from behind the diaphragm yet permitting free leakage therethrough. 105

4. An acoustical device of the class described, comprising in combination, a cupped back plate centrally supporting a driving motor; a reentrant conical diaphragm secured to the back plate concentric with the motor and being drivingly connected thereto; a thinly disced face plate secured to the said back plate to enclose said diaphragm and motor; means securing said diaphragm and face plate to the back plate concentric to the said motor; studs separating the plates and diaphragm from each other, and providing air flow about the edge of said diaphragm; and means mounting said acoustic device thus constructed upon the top bows of an automotive vehicle roof without substantially marring the contour of said roof. 120

5. In an acoustical device the combination

comprising, a back plate of shallow cup formation; a driving motor secured centrally of the plate; said plate providing concentric rows of spaced studs; a diaphragm peripherally secured from one row of studs and being centrally supported with respect to said motor; a grille secured to others of said stud substantially enclosing said motor and diaphragm; and a baffle of closely packed fibrous material between the diaphragm and back plate to effectively increase the air path of vibrations from the rear of the diaphragm.

6. The combination with the roof structure of an automotive vehicle of an acoustic device comprising; a back plate of shallow dished form having flanges; means to secure the plate at its flanges to the bows of said roof structure; a motor carried in the depressed portion of said plate; a reentrant conical diaphragm operatively connected to said motor; spaced studs carried by the back plate supporting the diaphragm at its edges, said studs spacing said diaphragm axially of said plate; fibrous material packed within the space between the diaphragm and the plate; a grille carried by the back member having free air access to both sides of the diaphragm except for the fibrous material; and means maintaining the said fibrous material from engagement with said diaphragm.

7. In an acoustical device of the electrodynamic type, the combination comprising a support providing a field coil; a reentrant conical diaphragm carried by the support and provided with a voice coil disposed for movement in the air gap of said field coil; studs supporting the diaphragm at its edge, and spacing the same from said support; baffle means interposed between the diaphragm and support to restrict free flow of air between alternate sides of the diaphragm, yet permitting free leakage therefrom; and a grille supported from the said plate cooperating with the same to enclose the elements of said dynamic unit.

8. An acoustical device of the class described, comprising in combination; a back plate supporting a motor at its center; a foraminous face plate secured at its periphery to the back plate; supporting studs for the face plate and spacing it from said back plate so as to substantially enclose the acoustical device; a diaphragm supported at its edge from said back plate; means spacing the diaphragm from both of said plates so as to provide a normally connected air passage between the front and back of said diaphragm about the edge thereof; and a pad of sound absorbing material secured against said back plate and substantially filling the space between the diaphragm edge and the back plate.

9. An acoustical device of the class described, comprising in combination; a back

plate supporting a motor at its center; a foraminous face plate secured at its periphery to the back plate; supporting studs for the face plate and spacing it from said back plate so as to substantially enclose the acoustical device; means provided by the back plate for securing the device to the roof structure of an automotive vehicle; and means provided by the face plate giving access to the securing means, without disturbance of the contributing parts of the device as assembled.

10. An acoustical device for automotive vehicles, comprising in combination; a pair of dished plates forming an enclosure for said device; studs located at the edge of one of said plates, securing them together; a diaphragm interposed between the plates, with means spacing it from each plate to provide an air passage about the diaphragm edge and between it and each of said plates; supporting studs spaced about the edge of said diaphragm securing the same to one of said plates; a motor drivingly associated with said diaphragm; and sound absorbing material packed in the space between the diaphragm and its supporting plate to restrict the air flow about the edge of said diaphragm.

In testimony whereof I hereto affix my signature.
